METHOD FOR TREATING OILS

Ulric B. Bray, Palos Verdes Estates, Calif., assignor to Union Oil Company of California, Los Angeles, Calif., a corporation of California

Application May 23, 1933, Serial No. 672,432

9 Claims. (Cl. 196—13)

The present invention relates to a method for separating asphalt from oil. More specifically, it relates to a method for separating asphalt from asphalt containing oils in a plurality of stages. 5 This invention is a continuation, in part, of my co-pending applications Serial No. 466,189, filed July 7, 1930; Serial No. 610,130, filed May 9, 1932 and Serial No. 659,854, filed March 6, 1933.

In my co-pending application Serial No. 10 466,189, I disclosed a two-stage process for the separation of asphalt and wax from crude oils or topped crudes containing the same to produce lubricating oil. In the first stage of the process, the asphalt and wax containing oil was commingled with a liquefied normally gaseous hydrocarbon solvent, such as liquid propane, under pressure sufficient to maintain the propane in a liquid state. This permitted the asphalt to precipitate from the solution of oil and propane 15 and settle to the bottom of the decanter. The oil solvent solution was separated from the precipitated asphalt and was then chilled by evaporating a portion of the propane under reduced pressure. This caused the wax to precipitate from 20 the solution. The wax was separated and then the propane was removed from the remaining oil solvent solution to produce a lubricating oil which was substantially free from asphalt and wax.

In my co-pending application Serial No. 30 610,130, I disclosed a process for the co-precipitation of asphalt and wax by means of a liquefied normally gaseous hydrocarbon solvent, in particular, liquid propane, wherein the asphalt and wax containing oil was commingled with the solvent under pressure sufficient to maintain the 35 solvent in a liquid state. The oil dissolved in the liquid propane and the asphalt was thrown out of solution. A portion of the liquid propane was allowed to vaporize under reduced pressure to chill the mixture of oil, solvent, wax and asphalt to a sufficiently low temperature to cause precipitation of the wax. The ebullition or boiling which accompanies the vaporization of the liquid propane caused a violent agitation of the mass and the precipitated asphalt acted as nuclear or gathering bodies for the agglomeration of the wax as it was precipitated at the lower temperature attained. The agglomerated particles of wax and asphalt were then separated from the oil solvent solution and the solvent was removed from the oil. This oil was a lubricating oil substantially 40 free from asphalt and wax.

In the foregoing process, I have observed that the lubricating oil produced is also free from the 45 heaviest viscous oil fractions and has a lower

Conradson carbon value. It is my belief that the presence of these heavy viscous oil fractions in lubricating oils are largely responsible for the high Conradson carbon values of lubricating oil. Such fractions were thrown out of solution by 5 chilling the oil containing both asphalt and wax and settled to the bottom of the decanter. In other words, I have discovered that chilling an oil to precipitate wax will also effect precipitation of the heavy viscous oil fractions, which, when 10 separated from the oil, will produce a lubricating oil of lower Conradson carbon value than when such fractions are retained in the lubricating oil.

In my co-pending application Serial No. 659,854, I disclosed a process for the co-precipitation of asphalt and heavy viscous oil fractions from asphalt containing residues substantially free from wax. Such precipitation was effected by mixing a liquefied normally gaseous hydrocarbon solvent, in particular, liquid propane, with 15 the asphalt containing oil under pressure sufficient to maintain the solvent liquid and then reducing the pressure on the mixture to permit evaporation of a portion of the propane which chilled the oil solvent solution and precipitated 20 the asphalt and heavy viscous oil fractions from solution. The precipitated mixture was removed from the oil solvent solution and was then heated to vaporize residual propane. The asphalt was recovered as a mixture of hard bitumen and heavy 25 viscous oil fractions. The oil solvent solution substantially free from asphalt and heavy viscous oil fractions was de-propanized and a lubricating oil having a low Conradson carbon value was 30 thus produced.

In the present discussion of my invention, by the term "propane", I intend to include such hydrocarbons as are normally vaporous at ordinary temperature and pressure; such hydrocarbons include methane, ethane, propane, butane, 40 isobutane and mixtures thereof. These normally gaseous hydrocarbon solvents may be obtained by rectification of casinghead gasoline by the so-called "stabilizing" method now conventional in the natural gasoline industry. They are the 45 overhead obtained. They are liquefied by compression and cooled in the conventional manner and are drawn off into pressure chambers where they are maintained in a liquid state until used. A typical analysis of such a fraction is 6.72% 50 ethane, 72.2% propane, 19.91% isobutane and 1.17% normal butane. Such a fraction may be maintained in a liquid state at a pressure of 125 lbs. per square inch at a temperature of about 55 75° F. The predominating hydrocarbon member

in this mixture is propane and hereafter when I use the word "propane" or "liquid propane" I am referring to such a fraction.

The present invention is also related to a treatment of asphaltic oils which are substantially free from wax. As stated in my aforementioned co-pending application, Serial No. 659,854, substantially all petroleum oils and particularly asphalt containing oils contain such heavy viscous oil fractions irrespective of whether they contain wax. It will be observed that all asphaltic oils contain more or less wax; some contain large quantities of wax, while others are substantially free but nevertheless contain a small quantity. Thus, such California crude oils as McKittrick, Poso Creek, Coalinga, Summerland and Sunset are typical asphaltic crudes containing very little wax, while other crudes as Montebello, Kettleman Hills, Santa Fe Springs, Elwood, Torrance and Santa Barbara are classed as mixed base crudes, that is, they contain large quantities of wax as well as asphalt. Nevertheless, substantially all of these oils contain high molecular weight bodies which are responsible for the high Conradson carbon value of lubricating oils. In treating oils substantially free of wax, it is customary to maintain the temperatures for separation of asphalt at approximately atmospheric, i. e. about 70° F. to 80° F. At such temperatures, the heavy viscous oil fractions are soluble in the oil solvent solution and will not precipitate from solution. My present invention is directed towards removal of such fractions from oils. It is particularly directed to treatment of asphaltic non-waxy oils. However, as will be described below and as has been stated above, it is also applicable to asphaltic wax containing oils.

By the present invention, I propose to separate the asphaltic material in asphalt containing oils substantially free from wax in a plurality of stages, in particular, in two stages. I have now discovered that I may precipitate and recover two entirely different types of asphalt, that is, a hard asphalt and a soft asphalt, if the precipitation by solvents and separation is effected in two stages. In one stage of the process, the oil containing asphalt is mixed with a liquefied normally gaseous hydrocarbon solvent under pressure sufficient to maintain the solvent in the liquid state to precipitate hard asphaltic material and at a temperature of substantially atmospheric, i. e. about 70° F. to 80° F. The precipitated asphaltic material is separated from the oil solvent solution and then the oil solvent solution which has been freed from the hard asphalt is chilled in a second stage to a sufficiently low temperature, i. e. about -40° F. to 0° F. to precipitate further quantities of asphaltic material. The character of the asphalt recovered in the first stage comprises a substantially hard asphalt or substantially pure bitumen, while the asphaltic material recovered in the second stage comprises the heavy viscous oil fractions aforementioned which are soluble in the oil solvent solution at atmospheric temperatures. Chilling of the oil solvent solution from which the hard asphalt has been removed will congeal such heavy viscous oil fractions and cause them to precipitate out of solution.

It will be observed that by the term "asphalt" I intend to include such asphaltic and non-waxy fractions which will separate or precipitate from asphalt containing oils when these oils are com-

mingled with liquid propane or other solvents. Thus, the heavy viscous oil fractions precipitated from solution by means of solvents at low temperatures will be considered an asphalt or asphaltic material as well as the hard asphalt or substantially pure bitumen separated from the oil in the first stage at atmospheric temperature. Such asphaltic material recovered in the second stage may be considered a secondary asphalt or a pseudo asphalt. It is of light brown color and of about road oil consistency.

If this process is operated on a waxy oil, the wax will precipitate with the viscous oil fractions in the second stage depending on the temperature at which the second precipitation is accomplished.

With the above discussion in mind, it will be perceived that it is an object of my invention to separate asphalt from an asphalt containing oil by means of a solvent in a plurality of stages, the first stage or stages being operated at a higher temperature than the second or subsequent stages.

It is a further object of my invention to separate asphalt from oils by means of solvents in two stages wherein a substantially hard asphalt is precipitated and separated in the first stage and a soft asphalt is precipitated and separated in the second stage, the precipitation and separation in the second stage being carried out at a lower temperature and pressure than that in the first stage.

A further object of my invention resides in commingling an asphalt containing oil substantially free from wax with a liquefied normally gaseous hydrocarbon solvent under pressure sufficient to maintain the solvent in a liquid state and at atmospheric temperatures of about 70° F. to 80° F. to precipitate a substantially hard asphalt, separating the precipitated asphalt from the oil solvent solution and then reducing the temperature of the oil solvent solution to approximately -40° F. to 0° F. by lowering the pressure to effect vaporization of a portion of the solvent and thus precipitate heavy viscous oil fractions or malthas or secondary soft asphalt, separating the latter precipitated asphalt from the oil solvent solution and then separating the solvent from the oil.

Other objects and advantages of my invention will be apparent from the following description of my invention taken from the drawing which refers to a schematic arrangement of apparatus for carrying out my invention.

Referring to the drawing, an asphalt containing oil substantially free from wax is taken from tank 1 and is drawn into line 2 by pump 3 where it meets a liquefied normally gaseous hydrocarbon solvent such as liquid propane taken from storage tank 4 via line 5 and pump 6 which forces the liquid propane through valve 7 into line 2. The amount of propane introduced into line 2 will depend upon the character of the oil and the temperatures desired in the second asphalt precipitator or decanter 8. The mixture of liquid propane and residuum is passed through turbulence or mixing coil 8 into the first decanter or asphalt precipitator 9 where the asphalt in the topped residuum is precipitated and settles rapidly as a slurry of substantially pure bitumen or hard asphalt containing some oil and propane. A pressure of approximately 125 lbs. per square inch and a temperature of about 70° F. to 80° F. is maintained in the decanter 9. This pressure will be sufficient to maintain the propane liquid

in decanter 9. The amount of propane introduced into the oil will also depend upon whether it is desired to remove the asphalt at the bottom of decanter 9 as a liquid fraction, the volumetric ratio of propane to oil in decanter 9 will be within a range of 0.6-6 to 1, depending upon the character of the oil and the degree to which it was topped. Higher volumetric ratios will precipitate the asphalt as a slurry of substantially pure bitumen and propane.

The asphalt precipitated in decanter 9 is withdrawn via line 10 controlled by valve 11 and is forced by pump 12 under pressure through heating coil 14 where it is heated to a sufficiently high temperature to melt the asphalt and vaporize residual propane. The heated mixture is then passed through line 15 and flashed through pressure reduction valve 16 on line 15 into evaporator 17 which operates at a lower pressure. Superheated steam is introduced into the evaporator 17 through perforated pipe 18 to supply additional heat and to reduce the asphalt to the proper specification, generally only as regards flash and fire points. The overhead from evaporator 17 passing through mist extractor 19 is sent through line 20 to cooler 21 and then to separator 22. The uncondensed propane from separator 22 is sent through line 23 controlled by valve 24 to lines 25, 26 and 27, to the suction of compressor 28, where its pressure is raised to that in the high pressure system and is then sent via line 29 to cooler 30 where it liquefies and runs down into propane storage tank 4. Any condensed light oil in separator 22 is withdrawn through line 31 and condensed water through line 32. The asphalt is taken from the bottom of the evaporator 17 and sent through line 33 controlled by valve 34 to storage tank 35.

The over-flow from decanter 9 consisting of propane and oil free from hard asphalt and also wax but containing heavy viscous oil fractions, tars, maltha or pseudo asphaltic material is sent through line 36 and pressure reduction valve 37 into the second decanter or asphalt precipitator 38. In decanter 38 sufficient propane vaporizes to reduce the temperature of the remaining material to a sufficiently low temperature which causes the aforementioned heavy viscous oil fractions and the like to precipitate from solution. The desired low temperature is obtained by controlling the pressure in decanter 38 by the proper operation of valve 40 on line 39 and compressor 28 which is connected to the decanter by lines 27 and 39. The pressure to be maintained in decanter 38 will generally be about 0 to 25 lbs. gauge which corresponds to a temperature of approximately between -40° F. to 0° F. As the propane solution passes through valve 37, its pressure is reduced so that a portion of the propane evaporates in the decanter 38 and vapors pass out of the top through line 39 controlled by valve 40 and then into lines 26 and 27 to the suction of compressor 28 where the vapors are compressed, pass through line 29, liquefied in cooler 30 and run down to propane storage tank 4. An equilibrium line 41 controlled by valve 42 connects the decanter 9 with the high pressure storage tank 4.

The material precipitated in decanter 38 settles to the bottom of the decanter and is removed by line 43 controlled by valve 44 and pump 45 as a mixture of propane and heavy viscous oil fractions and asphaltic material which was not separated in the first decanter 9. Due to the light character of the material precipitated in decanter

38, sufficient settling time must be provided to the asphaltic material to stratify from the solution of oil and propane. If desired, decanter 38 may be operated as a chilling column without effecting settling of the precipitated material. The chilled mixture may then be passed to a plurality of settling chambers operated alternately when sufficient time may be provided to permit the precipitated asphaltic material to settle or stratify from the oil solvent solution. The precipitated asphaltic material may then be removed from the bottom of the settling chamber as a product substantially free from the lubricating oil fractions. Pump 45 forces the mixture settling at the bottom of decanter 38 under pressure through heating coil 46 where it is heated to a sufficiently high temperature to render the precipitated material fluid and to vaporize residual propane. The heated mixture is then passed into line 47 and flashed through pressure reduction valve 48 on line 47 into evaporator 50 which operates at a lower pressure. Superheated steam is introduced into evaporator 50 through perforated pipe 51 for supplying additional heat and to reduce the asphaltic and viscous heavy oil fractions to a proper specification, such as flash and fire points. The overhead from evaporator 50 passing through mist extractor 52 is sent through line 53 to cooler 54 and then to separator 55. The uncondensed propane from separator 55 is sent through line 56 controlled by valve 57 to lines 25, 26 and 27, to the suction of compressor 28, where its pressure is raised to that in the high pressure system and is sent via line 29 to cooler 30 where it liquefies and runs down into propane storage tank 35. Any condensed light oil in separator 55 is withdrawn through line 58 and condensed water through line 59. The pseudo asphaltic material or heavy viscous oil fractions is taken from the bottom of evaporator 50 and sent through line 60 controlled by valve 61 to storage tank 62.

The over-flow from decanter 38 consisting of propane and oil free from asphalt and heavy viscous oil fractions, malthas and the like and also wax is sent through line 65 by pump 66 and 45 then through line 67 controlled by valve 68 to acid treatment and neutralization with alkali, valve 70 on line 69 being closed. If desired, valve 68 on line 67 may be closed and valve 70 on line 69 opened so that the over-flow from decanter 38 may pass into line 69 and then through valve 70 into evaporator or heater 71 provided with mist extractor 72 where the propane present is vaporized by the aid of steam circulated through the closed steam coil 73. The vaporized propane passes out of the heater through line 74 controlled by valve 75 and then passes through cooler 76 into lines 78 and 27, to compressor 28, cooler 30 into storage tank 4. The depropanized oil passes from heater 71 by means of line 79 controlled by valve 80 into storage tank 81. This oil will comprise a lubricating oil of low Conradson carbon value and will be substantially free from heavy viscous oil fractions, wax and asphalt. The oil may be acid and alkali treated prior to its use or may be treated by other methods now conventional. If desired, the over-flow from decanter 38 may be acid and alkali treated in the presence of propane under pressure prior to depropanization in heater 71.

It is to be understood that the above is merely illustrative of preferred embodiments of my invention of which many variations may be made by those skilled in the art without departing from the spirit thereof.

I claim:

1. A process for the separation of asphalt from oil which comprises commingling said oil with a liquefied normally gaseous hydrocarbon solvent to precipitate asphalt, removing the precipitated asphalt from the oil and solvent, chilling the oil and solvent to precipitate a further quantity of asphalt and removing said second precipitated asphalt from the oil and solvent.
- 5 2. A process as in claim 1 in which the liquefied normally gaseous hydrocarbon solvent contains a substantial proportion of propane.
- 10 3. A process for separating asphalt from oils containing the same but which are substantially free from wax which comprises mixing said oil with a liquefied normally gaseous hydrocarbon solvent and precipitating the asphalt from the oil and solvent in a plurality of stages.
- 15 4. A process for separating asphalt from oils containing the same but which are substantially free from wax which comprises mixing said oil with a liquefied normally gaseous hydrocarbon solvent to precipitate asphalt, separating said precipitated asphalt from the oil solvent solution and chilling said oil solvent solution to precipitate further quantities of asphalt and separating said second precipitated asphalt from the oil solvent solution.
- 20 5. A process for separating asphalt from oils containing the same but which are substantially free from wax which comprises mixing said oil with a liquefied normally gaseous hydrocarbon solvent under superatmospheric pressure and precipitating the asphalt from the oil solvent solution in a plurality of stages, the second of said stages being operated at a lower temperature than the first stage.
- 25 6. A process for separating asphalt from oils containing the same but which are substantially free from wax which comprises mixing said oil with liquid propane under superatmospheric pressure and precipitating asphalt from said mixture in two stages, the first of said stages being operated at a higher temperature and pressure than the second of said stages whereby a
- 30 substantially hard asphalt is precipitated in said first stage and a substantially soft asphalt is precipitated in said second stage.
- 35 7. A process for separating asphalt from oils containing the same but which are substantially free from wax which comprises mixing said oil with a liquefied normally gaseous hydrocarbon solvent under superatmospheric pressure to precipitate asphalt, separating said precipitated asphalt from the oil solvent solution and reducing the pressure on said oil solvent solution to vaporize a portion of the solvent to chill the oil and precipitate further quantities of asphaltic material and separating said further quantities of precipitated asphaltic material from the oil solvent solution.
- 40 8. A process for separating asphalt from oils containing the same but which are substantially free from wax which comprises mixing said oil with liquid propane under pressure sufficient to maintain said propane liquid to precipitate asphalt, separating said precipitated asphalt from the oil and propane solution, releasing the pressure on the oil and propane to vaporize a portion of the propane and thus chill the oil to precipitate further quantities of asphalt, separating said further quantities of precipitated asphalt from the oil and propane and separating the propane from the oil.
- 45 9. A process for separating asphalt from oils containing the same but which are substantially free from wax which comprises mixing said oil with propane under pressure sufficient to maintain the propane liquid to precipitate a substantially hard asphalt and at substantially atmospheric temperature, separating said precipitated hard asphalt from the oil propane solution, reducing the pressure on the oil propane solution to vaporize a portion of the propane and thus chill the oil to precipitate a soft asphalt, separating said precipitated soft asphalt from the oil and remaining propane and separating the remaining propane from the oil.

ULRIC B. BRAY. 45
